UNITED STATES PATENT OFFICE.

THEODORE DANNER, OF MILTON, OREGON.

DOOR-SECURER.

1,316,223.

Specification of Letters Patent. Patented Sept. 16, 1919.

Application filed September 30, 1918. Serial No. 256,257.

To all whom it may concern:

Be it known that I, THEODORE DANNER, a citizen of the United States, residing at Milton, in the county of Umatilla and State of Oregon, have invented certain new and useful Improvements in Door-Securers, of which the following is a specification.

This invention relates to builders' hardware, and more especially to door securers, and the object of the same is to produce a device of this character capable of ready application to a door which has either a rim lock or a mortise lock. These devices, as is well known, are usually carried by traveling men and employed for locking the doors of rooms in hotels and other questionable apartments, where the door lock is defective or suspicious, or minus a key; and these devices become highly useful if the operator has money with him, or perhaps carries valuable goods in his grip. There are door securers which embed the wood of the frame and the edge of the door, between which elements they are inserted; but it is the purpose of my present invention to produce a device of this kind which does not injure the wood-work and which is yet applicable to the parts of either lock as mentioned above.

Details are set forth below, and reference is made to the accompanying drawings, in which:

Figure 1 is a plan view of this device showing the parts at one end thereof in use on a door which has a mortise lock,

Fig. 2 is a similar view showing the parts at the other end of the device in use on a door which has a rim lock.

Fig. 3 is a side view of the parts with its various members swung out of alinement with each other to afford better illustration.

I prefer to make this device double-ended, the shank of the structure at one end extending into and preferably being pivotally connected with the shank of the structure at the other end. The parts at one end are adapted for use on a mortise lock and those at the other end for use on a rim lock. However, it will be shown that the structure of the first named parts is such that they might be used on a rim lock. The entire device is so small that it may be folded and carried in the pocket, or in the grip. It is made of strap metal preferably nickelized to give it a neat appearance and to prevent rust, and the exact proportions and details are not important. I have used letters to indicate the

door D, the jamb J with its door-stop S, the casing C, and the trim T. There is supposed to be a lock within the door D of Fig. 1, but this view illustrates a mortise as indicated at M and a keeper plate P which is engaged by the bolt of the lock when projected. A rim lock is indicated at L in Fig. 2, and its bolt when projected will engage a keeper K as shown. No novelty is claimed for the parts thus far described. The shank 1 of the door securer shown in Fig. 1 is a straight bar having a right-angular hook 2 at its inner end, a slot 3 in its body, a series of holes 4 in said body farther to the rear, and its rear end bent as at 5. Against one side of said shank lies a flat leg 6 having a slot 7 in its body and an outturned foot at its inner end as at 8, its rear end preferably being notched as at 9. Pivoted at 10 to this leg is a button 11 having an operating knob 12 and at its free end a pin 13 which moves in said notch 9 from side to side and is adapted to be engaged with one of the holes 4 to the shank 1. Connecting the leg and the shank and passing through the slots therein is a bolt 14 having a thumb-nut 15 screwed thereon as best seen in Fig. 1. Lying against the other side of the shank 1 is another leg 16 which may have its body slotted or not as desired, but the bolt 14 passes through said body as will be seen in Fig. 1. The inner end of this leg has a foot 18 outturned from it and preferably looped as shown in Fig. 1.

In use on a door having a mortise lock, the thumb-nut 15 is loosened and the bolt 14 slid back within the slot 3 of the shank 1, the legs 6 and 16 being swung on said bolt as a pivot. The door D now being opened the operator places the hook 2 within the mortise M and the shank 1 alongside the keeper plate P, then he closes the door, and finally he swings the legs until the foot 18 stands between the shank and the trim T and the foot 8 lies against the face of the door; and then he sets up the thumb-nut tightly. The door is now securely fastened, whether the bolt of the lock be shot or not, and in fact whether the lock is in order or has any bolt at all, so long as there is a mortise M within the casing C.

The structure at the other end of the device is much the same in some particulars, and yet adapted to a different use. Here the shank 21 (whose rear end may be pivoted at 20 to the bend 5 of the first-named shank)

has a hook 22 at its inner end adapted to engage within the keeper K of a rim lock as shown. Alongside this shank stands a link 26 having a foot 28 at its inner end, and 5 along the opposite side another leg 36 having a foot 38 at its inner end, a bolt 24 passing through both legs and receiving a thumb-nut 25. This bolt between the legs passes through a slot in the shank 21, which 10 slot may open out the edge thereof as seen in Fig. 3, and therefore might be said to be a notch as indicated at 23. When the thumb-nut is loosened, it is obvious that the two legs can be moved out of alinement with 15 the shank, but at their rear ends they are pivoted thereto as at 30. Thus the parts have not the longitudinal adjustment upon each other which is possessed by the type of 20 my invention shown in Fig. 1, but they are capable of use as I will now describe.

When this end of the device is applied to a door having a rim lock, the nut is loosened and the legs swung aside, the door D is opened, the hook 22 passed into the keeper 25 K as shown in Fig. 2, the door closed, the legs swung back into place and the bolt 24 dropped into the slot or notch 23, and the thumb-nut 25 reset. The foot 28 now bears 30 against the lock L and the foot 38 against the face of the keeper, but the door D cannot be swung open so long as the keeper remains screwed to the casing C. Therefore 35 this device fastens the door whether the lock bolt is projected or not, and whether, in fact, it can be projected, as its safety and utility depend on the presence and rigidity of the keeper.

What is claimed as new is:—

1. In a door securer, the combination with 40 a straight shank having a right-angular hook at its inner end and a longitudinal slot in its body, a pair of legs lying against opposite sides of said shank and having out-turned feet at their inner ends, their bodies 45 having slots, a bolt through all said slots,

and a thumb-nut on said bolt; of a button pivoted to the rear end of one leg and movable over the outer face thereof, the outer extremity of this leg being notched and the shank having a series of holes in its body, 50 and a pin at the free end of said button passing through said notch and adapted to enter one of said holes, for the purpose set forth.

2. In a door securer, the combination with 55 a straight shank having an angular hook at its inner end and a longitudinal slot, a leg lying against one side of said shank and having an outturned foot at its inner end, its body having a slot, a bolt passing through 60 said slot and a thumb nut on said bolt, of a button pivoted to the rear end of said leg and movable over the outer face thereof, the outer extremity of said leg being notched and the shank having a series of holes in its 65 body, and a pin at the free end of said button passing through said notch and adapted to enter one of said holes, for the purposes set forth.

3. In a door securer, the combination with 70 a straight shank having a hook at its inner end, a leg lying against one side of said shank and having an outturned foot at its inner end, means for guiding said leg in movement upon said shank, of a button pivoted to the rear end of said leg, and movable over the outer face thereof, the outer extremity of said leg being notched and the shank having a series of holes in its body, 75 and a pin at the free end of said button passing through said notch and adapted to enter one of said holes for the purposes set forth.

In testimony whereof I affix my signature in presence of two witnesses.

THEODORE DANNER.
